CLAIM

The ornamental design of a vehicle anchor, substantially as shown and described.

DESCRIPTION

FIG. 1 is a top-front perspective view of a vehicle anchor in accordance with the present design;

FIG. 2 is a front elevation view thereof;

FIG. 3 is a back elevation view thereof;

FIG. 4 is a first-side elevation view thereof;

FIG. 5 is a second-side elevation view thereof;

FIG. 6 is a top view thereof; and,

FIG. 7 is a bottom view thereof.

The broken lines in the Figures show portions of the vehicle anchor which form no part of the claimed design.
